UNITED STATES PATENT OFFICE

121,707

DESIGN FOR A BEVERAGE BOTTLE OR SIMILAR ARTICLE

Ralph A. Vogel, Norbert J. Mulligan, and Frank H. Vogel, Columbus, Ohio, assignors to Wyandotte Mineral Water Inc., Columbus, Ohio, a corporation of Ohio

Application April 11, 1940, Serial No. 91,616

Term of patent 14 years

To all whom it may concern:

Be it known that we, Ralph A. Vogel, Norbert J. Mulligan and Frank H. Vogel, citizens of the United States, residing at Columbus, in the county of Franklin and State of Ohio, have invented a new, original, and ornamental Design for a Beverage Bottle or Similar Article, of which the following is a specification, reference being had to the accompanying drawing, forming a part thereof.

Fig. 1 is a perspective view of a beverage bottle or similar article showing our new design; and

Fig. 2 is a side elevational view thereof.

We claim:

The ornamental design for a beverage bottle or similar article, as shown.

RALPH A. VOGEL.
NORBERT J. MULLIGAN.
FRANK H. VOGEL.
